UNITED STATES PATENT OFFICE.

EDGAR SHOCK, OF WASHINGTON, DISTRICT OF COLUMBIA, ASSIGNOR OF ONE-THIRD
TO HORACE F. CLARK, OF WASHINGTON, DISTRICT OF COLUMBIA.

DOOR-CHECK.

1,051,826.

Specification of Letters Patent. Patented Jan. 28, 1913.

Application filed June 8, 1912. Serial No. 702,521.

To all whom it may concern:

Be it known that I, EDGAR SHOCK, a citizen of the United States, residing at Washington, in the District of Columbia, have 5 invented new and useful Improvements in Door-Checks, of which the following is a specification.

My invention relates to devices for use particularly on doors, gates and other closures, and constructed to close the door or other closure by spring action.

In carrying the invention into effect I provide a spring check which comprises co-operating surfaces associated with the respective hinged members, one of the surfaces at least being oblique and one yieldingly or spring mounted, the surfaces being arranged to engage and ride one upon the other so as to constitute a check.

20 The invention consists in the novel construction and arrangement of parts of a door check hereinafter described and shown in the accompanying drawings, to which reference may be had for a more complete understanding of the invention.

In the drawings, Figure 1 is a face view of a device made in accordance with the invention; Fig. 2 is a similar view showing one member opened to ninety degrees; Fig. 3 is a similar view showing one member entirely open; and Fig. 4 is a plan view, on a reduced scale, showing in whole lines the device in Fig. 2 position, and in dotted lines the Figs. 1 and 3 positions.

25 Referring to the drawings, A and B indicate the portions of two members adapted to be secured one to the door and the other to the door frame, or to other parts which are to be operated upon by the check. Of 30 these members, A is provided with lugs *a*, *a'*, and member B is provided with lugs *b*, *b'*, each lug being provided with a perforation for the reception of pivot or hinge pin C by which the members are pivotally connected together. Lugs *a*, *a'* are spaced apart from each other for the purpose hereinafter referred to, and lugs *b*, *b'* are located toward the upper and lower ends of plate B preferably so as to be spaced from lugs *a*, *a'*, these latter spaces being provided for springs D, D', one end of each spring bearing against or engaging plate A and the other end engaging or bearing against plate B.

35 *E*, *E'* represent movable abutments slid- 40 ingly mounted upon pivot pin C, and lo-

cated preferably between lugs *a* and *a'*. These movable abutments are connected with plate B, preferably by having their ends project into a slot or channel *b*² on the inner edge of plate B.

60

The two members hinged together as above described move in conjunction with co-operating cam surfaces, one of these surfaces being oblique to the line of motion of the hinged members when the members are 65 moved upon their pivot. These surfaces are represented at *e*, which is shown as the principal oblique surface, and *e'* the other co-operating surface. These co-operating surfaces are shown in duplicate, one pair being 70 upon lug *a* and abutment *E*, and the other pair being upon lug *a'* and abutment *E'*. The abutments *E* and *E'* are yieldingly or spring mounted, preferably by an interposed spring F which is compressed when the 75 abutments are moved toward each other.

The slot or channel *b*² may be utilized for the reception of the end *d* of spring D, and the end *d'* of spring D'.

It is not intended that the structure shown 80 and described should constitute a hinge for the door or other closure and support any weight, but with slight changes it may be made to perform also the function of a hinge. For instance, the portion of lugs *a*, 85 *a'* surrounding the pin C might be extended outwardly to engage lugs *b*, *b'*, and the springs D and D' be coiled about these extensions.

The operation of the device will be clear 90 from the foregoing description.

With the parts in the positions shown in Fig. 1, the door or other closure is in its closed position, spring F being compressed. When the door is opened the outward edge 95 of surfaces *e*' moves downwardly along inclines *e* of movable abutments *E* and *E'*, permitting spring F to expand until when the door is in the predetermined position, for instance ninety degrees, as shown in Fig. 100 2, spring F will be fully expanded and any movement of the door beyond this angle will cause a disengagement of the co-operating surfaces *e*, *e'*. When the door is opened all the way back, as shown in Fig. 3, or is 105 opened farther than the predetermined angle, the co-operating surfaces will no longer exert pressure upon each other.

When the door starts to close, under the action of springs D, D' or under any other 110

influence, its movement will be unimpeded until it has passed a predetermined angle, say ninety degrees in the instance illustrated, when the coöperating surfaces will be engaged, and by surfaces *e* riding upon inclined surface *e'* riding upon inclined surface *e* will move the movable abutments against the action of spring *F* in order to check the movement of the door during the latter portion of its closing.

10 Of course the arrangement of the surfaces and the strength of the various springs will be made to conform to requirements. That is, the surfaces may be arranged to engage during a greater or less proportion of the 15 closing movement of the door. It will also be obvious that numerous other changes in proportion and arrangement of parts may be made without departing from the scope of the invention.

20 Having described my invention, what I claim as new, and desire to secure by Letters Patent of the United States, is—

1. A door check comprising hinged members, a pair of movable abutments slidingly mounted upon the pivot of said hinged members and splined to one member, a spring between said abutments, for pressing the same in opposite directions said movable abutments and the other member provided with coöperating surfaces one of which is of considerable extent and inclined to the line of motion of the other surface so as to resist the closing motion of the movable member, said movable abutments being spaced between the surfaces coöperating therewith, so as to be lifted idly by one of the coöperating surfaces during the first part of the closing movement and said spring then compressed to check the closing movement.

40 2. A door check comprising hinged mem-

bers, one of said members provided with lugs spaced apart and perforated to receive the pivot of the members, said pivot, and a pair of movable abutments slidingly mounted upon the pivot and splined to the other member, a compression spring on said pivot between said abutments, said movable abutments having surfaces of considerable extent inclined to the line of motion of a point on said lugs so as to resist by compression of 50 said spring the closing motion of the movable member.

3. A door check comprising hinged members one of which has perforated end lugs for the pivot, a pair of movable abutments 55 slidingly mounted upon the pivot of said hinged members and splined to the member having end lugs, a spring between said abutments for pressing the same in opposite directions, the other member having a perforated lug upon each side of said movable abutments and spaced from the end lugs of the first member, said movable abutments and the second pair of lugs provided with coöperating surfaces of which one is of considerable extent and inclined to the line of motion of the other surface so as to resist the closing motion of the movable member, a pivot pin passing through said lugs, and springs on said pin between each end lug 70 and the adjacent inner lug and bearing on said members to cause the closing motion.

In testimony whereof I have hereunto set my hand in presence of two subscribing witnesses.

EDGAR SHOCK.
